UNITED STATES PATENT OFFICE.

WILLIAM EDWARD STONE, OF MARBLEHEAD, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,030,836.

Specification of Letters Patent. Patented June 25, 1912.

Application filed November 29, 1901. Serial No. 84,094.

To all whom it may concern:

Be it known that I, WILLIAM E. STONE, a citizen of the United States, residing at Marblehead, in the county of Essex and 5 State of Massachusetts, have invented certain new and useful Improvements in Sewing-Machines; and I do hereby declare the following to be a full, clear, and exact description of the invention, such as will enable others skilled in the art to which it 10 appertains to make and use the same.

The present invention relates generally to shoe sewing machines and more particularly to shoe sewing machines of the wax-thread 15 chain-stitch type of which the commercial welt and turn sewing machines are examples.

The object of my invention is to improve the construction and operation of the thread handling devices and especially the tension 20 device and its co-operative relation with the stitch forming mechanism. I have also improved the machine in various other details hereinafter pointed out.

To the above end the present invention 25 consists in the devices and combinations of devices hereinafter described and claimed.

In the accompanying drawings illustrating the preferred form of my invention, Figure 1 is a sectional elevation of a chain-stitch turn shoe sewing machine embodying 30 my invention; Fig. 2 is a side elevation of a portion of the machine viewed from the opposite side from that illustrated in Fig. 1; Fig. 3 is a side elevation of the tension device and its actuating and controlling 35 mechanism; and Figs. 4, 5, 6 and 7 are diagrams illustrating the mode of operation of the machine showing the parts in different positions which they assume during the 40 operation of the machine.

In the illustrated embodiment of my invention I have shown it as adapted to a turn sewing machine of the "Lincoln" type, but it is to be noted that my invention is 45 susceptible of embodiment in various forms of machines whether welt or turn machines employing a curved hook needle, and, in its broader aspects, whether a thread finger be employed or not, although I prefer in order 50 to secure the best results with my invention to use it in connection with a thread finger. It is also to be noted that my invention is available for use in machines in which the stitch is set by a cam-actuated take-up as

well as in machines like the machine of the 55 drawings, in which no positively actuated devices other than the needle, looper, thread finger, and movable tension are employed to bring the stitch to its final position in the finished seam, although my invention is 60 probably more advantageously employed in machines of the latter class.

In the embodiment of my invention illustrated in the accompanying drawings the needle 1 is the usual curved hook needle 65 mounted in the usual needle segment 2 and actuated by the connecting rod 3 in the usual manner from a cam-path in a cam-disk mounted upon the main shaft S of the machine. The machine is provided with the 70 usual needle-guide 4. The looper 5 is of the rotary type being provided with the pinion 6 actuated by the rack 7 in the usual manner. The thread finger 8 is pivoted at 9 and actuated in the usual manner by the connected 75 rod 10 by means of the bell crank lever 11 pivoted upon a stationary part of the frame F of the machine which is actuated by a peripheral cam of one of the cam-disks 80 mounted upon the main shaft S of the machine. The channel-guide 12 is pivotally mounted upon the feed-slide and actuated in the usual manner from cams on the main shaft of the machine. The feed point 13 is also mounted upon the feed-slide and actuated in the usual manner by cams on the main shaft of the machine. The needle, needle-guide, looper, thread finger, channel-guide, and feed-point may be of any suitable 85 or preferred construction, and in and of 90 themselves form no part of my invention.

The tension device T consists of a tension wheel 14 revolvably mounted upon a lever 15 pivoted at 16 on a fixed part of the frame 95 of the machine. The usual friction-producing devices are provided for applying a frictional resistance to the rotation of the tension wheel. The tension wheel is acted upon by a spring 17 which is connected at one end to a stationary part of the frame of 100 the machine and at the other end to an adjusting screw 18 which passes through a hole in a downwardly projected portion 19 of the lever 15, an adjusting nut 20 serving to adjust the position of the adjusting screw 105 18 to vary the force exerted upon the lever 15 by the spring 17. The spring 17 normally tends to move the lever 15 in the di-

rection to keep the thread tight between the tension wheel and the stitch-forming mechanism, and in the illustrated embodiment of the invention said spring normally tends to move the tension wheel rearwardly.

Means are provided to move the tension wheel positively in the direction to give up thread to the stitch-forming mechanism. To the above end the connecting rod 21 is 10 pivotally connected at one end to the upper end of the lever 15, at the other end said connecting rod is connected with a lever 22 pivotally supported upon a stationary part of the frame of the machine. The lever 22 15 carries at its opposite end a cam roll 23 which engages a cam-path 24 in the cam-disk 25 secured to the main shaft S of the machine. The cam, the lever 22, and the connecting rod 21 constitute means for positively moving the tension wheel in the direction of the lead of the thread, *i. e.* forwardly, in order to positively give up thread to the stitch-forming mechanism. The connection between the connecting rod 20 21 and the lever 22 consists of a pin 26 secured to the end of the lever 22 and engaging a slot 27 in the end of the connecting rod 21. When the pin 26 engages the end of the slot 27 as shown in Fig. 1, the tension 25 wheel will be positively moved forward by means of the mechanism described and at the same time the tension wheel will be capable of moving forward under the strain exerted thereon by the thread when such 30 strain is sufficient to overcome the resistance offered to such movement by the strain of the spring 17.

Suitable stops are provided to limit the movements of the lever 15, and in the machine of the drawings the stop 28 limits the backward movement of the lever 15 and the adjustable stop 29, provided with the lock nut 30, limits the forward movement of the lever 15. The cam-path 24 for actuating 40 the tension wheel is so constructed that after the needle has advanced toward the work and begun to penetrate the same and during the time the thread finger 8 is forming a bight in the thread, the tension wheel 14 is 45 moved positively forward a short distance to positively give up thread to the thread finger during its bight-forming movement. Thereafter the cam-path 24 acts to move the tension wheel 14 positively forward to give 50 up thread to the looper during the time it is encircling the needle to lay the thread in the barb thereof. Again, the cam-path acts to positively move the tension wheel 14 forward to give up thread to the needle during 55 the first part of the retracting stroke of the needle. It is to be observed that during the bight-forming motion of the thread finger, during the looping-motion of the looper, and during the first part of the retracting 60 stroke of the needle, at which times thread is

required by these stitch-forming devices, the tension wheel is positively moved forward in the direction to give up thread to them. After these operations of the stitch-forming mechanism have been completed, the cam-path 24 acts to move the lever 22 in the direction to permit the tension wheel 14 to move rearwardly under the influence of its spring 17 and the cam-path 24 is preferably so constructed that this movement of the lever 22 is such as to move the pin 26 rearwardly in the slot 27, whereby the tension wheel is left under the sole control of the spring 17, so that the tension wheel 14 is therefore acted upon by its spring 17 to exert an uninterrupted yielding strain upon the thread during the final part of the retracting stroke of the needle while the needle is setting the stitch, with the result that the strain exerted upon the thread by the needle in setting the stitch is resisted by a spring pressure so that a stitch is set with a gradually increasing yielding strain on the thread with the attendant advantages recognized by those skilled in the art. While the best results will be secured by setting the stitch against an uninterrupted yielding action of the spring 17 as above stated, substantial benefits can be secured by an interrupted yielding action of the spring, such 85 for example as would occur if the projection 19 should contact with the stop 28 before the stitch setting strain was exerted on the thread, since it is important to prevent a sudden strain being brought on the thread 90 by stitch forming mechanism.

The operation of the machine illustrated in the accompanying drawings is as follows:—In Fig. 4 the needle is shown at the time during its forward movement when its point has entered the materials and after the thread finger has formed its bight of thread, and the tension wheel 14 is shown as having been moved positively forward by its cam and as having given up thread to the thread finger. The pin 26 at this time is in engagement with the end of the slot 27 so as to secure the mode of operation above stated. The needle then continues its forward movement into the position shown in Fig. 5, and the looper in that figure is shown as having completed its looping movement. During this forward movement of the needle from the position shown in Fig. 5 to the position shown in Fig. 6, the tension wheel 14 was moved by its cam farther forward to give up thread to the looper, the pin 26 remaining in engagement with the end of the slot 27. After the completion 110 of the looping of the thread in the barb of the needle, the needle begins its retracting stroke and the parts pass from the positions shown in Fig. 5 to the positions shown in Fig. 6, in which the needle is shown as having moved rearwardly until its barb has just 115 120 125 130

emerged from the materials. During this movement of the needle from the position shown in Fig. 5 to the position shown in Fig. 6, the thread finger has moved forward 5 giving up its bight of thread to one side of the loop of thread drawn back by the needle and the tension wheel 14 has moved forward under the influence of its cam, thus giving up thread to the other side of the loop of thread drawn back by the needle, the pin 26 remaining in engagement with the end of the slot 27. During the movement of the needle from the position shown in Fig. 6 to the position shown in Fig. 7, the lever 22 is 10 moved by its cam to move the pin 26 backward in the slot 27 and the tension wheel is now controlled solely by its spring 17 and the tension of the thread thereon, so that during the last part of the retracting stroke 15 of the needle while it is setting the stitch the tension wheel offers an uninterrupted yielding strain on the thread, whereby the stitch is set against a strain gradually increasing to the full tension resistance. During 20 the first part of the forward motion of the needle from the position shown in Fig. 7 to the position shown in Fig. 4, the tension wheel 14 moves rearwardly, shortening the loop of thread standing around the 25 shank of the needle. It is immaterial to my invention whether this shortening of the loop of thread held by the needle during its forward movement is sufficient to take all of the slack out of the loop by the time the 30 needle reaches the position shown in Fig. 4 or not, although I prefer that the loop at this time should have little, if any, slack 35 thread in it.

It is to be noted that my invention is not 40 limited to the embodiment thereof illustrated in the accompanying drawings, but is susceptible of embodiment in various forms of mechanism without departure therefrom, the accompanying drawings illustrating the best form now known to me and 45 one which is capable of effectively carrying out my invention.

It is also to be noted that if my invention 50 was embodied in a machine in which the stitch was set by a cam-actuated take-up, the timing of the movements of the various parts would be such that the take-up would exert its stitch-setting strain upon the thread during the time the tension wheel 55 was controlled solely by its spring.

Having thus described my invention, I claim as new and desire to secure by Letters Patent of the United States:—

1. A chain-stitch shoe-sewing machine, 60 having, in combination, stitch-forming mechanism including a curved hook needle, a movable tension wheel engaging the thread leading to the side of the work opposite to that on which the needle enters, 65 a cam for moving the tension wheel to posi-

tively give up thread to the stitch-forming mechanism, and a spring tending to move the tension wheel and arranged to yield so as to exert an uninterrupted yielding and gradually increasing strain on the thread during the setting of the stitch, substantially as described. 70

2. A chain-stitch shoe-sewing machine, having, in combination, stitch-forming mechanism including a curved hook needle, a movable tension wheel engaging the thread leading to the side of the work opposite to that on which the needle enters, a cam for moving the tension wheel to positively give up thread to the needle and a spring tending to move the tension wheel and arranged to yield so as to exert a yielding and gradually increasing strain on the thread during the setting of the stitch, substantially as described. 75

3. A chain-stitch shoe-sewing machine, having, in combination, stitch-forming mechanism including a curved hook needle, and a thread finger, a movable tension wheel, a cam for moving the tension wheel to positively give up thread to the thread finger, and a spring acting on the tension wheel to exert a strain on the thread during the setting of the stitch, substantially as described. 80

4. A chain-stitch shoe-sewing machine, having, in combination, stitch-forming mechanism including a curved hook needle, a looper and thread finger, a movable tension wheel, a cam for moving the tension 100 wheel to positively give up thread to the looper, and a spring acting on the tension wheel to exert a strain on the thread during the setting of the stitch, substantially as described. 105

5. A chain-stitch shoe-sewing machine, having, in combination, stitch-forming mechanism including a curved hook needle, a looper, and a thread finger, a movable tension wheel, a cam for moving the tension 110 wheel to positively give up thread to the needle, looper, and thread finger, and a spring acting on the tension wheel to exert a strain on the thread during the setting of the stitch, substantially as described. 115

6. A chain-stitch shoe-sewing machine, having, in combination, stitch-forming mechanism including a curved hook needle, a movable tension wheel engaging the thread leading to the side of the work opposite to that on which the needle enters, means for positively moving the tension wheel in one direction to give up thread to the stitch-forming mechanism, and a spring for moving said wheel in the opposite direction constructed and arranged to yield when the stitch is set and exert a gradually increasing strain on the thread, substantially as described. 120

7. A chain-stitch shoe-sewing machine, 125

having, in combination, stitch-forming mechanism including a curved hook needle, a movable tension wheel, cam-actuated means for moving the tension wheel in the direction to give up thread to the stitch-forming mechanism having provision for lost-motion permitting the tension wheel to be moved by the stitch-forming mechanism under the strain of the thread exerted thereon by said mechanism, and a spring normally tending to move the tension wheel in the direction to keep the thread tight between the tension wheel and the stitch forming mechanism, substantially as described.

15. 8. A chain stitch shoe-sewing machine, having, in combination, stitch forming mechanism including a curved hook needle, a pivoted lever, a tension wheel revolvably mounted on said lever, a cam lever, connections including a pin and slot connection between the cam lever and said first-mentioned lever for positively moving said first-mentioned lever in one direction, and a spring tending to move said first-mentioned lever

in the opposite direction, substantially as described.

9. A chain-stitch shoe sewing machine having, in combination, stitch-forming mechanism including a curved hook needle, a movable tension wheel engaging the thread leading to the side of the work opposite to that on which the needle enters, means for moving the tension wheel positively to give up thread to the needle during its retracting stroke, said means acting to give up less thread than the entire amount required for said needle stroke, and a spring controlling the tension wheel and permitting it to yield to give up a further amount of thread as the stitch is set, substantially as described.

In testimony whereof I affix my signature, in presence of two witnesses.
